A. S. SAMUELS.
HOLDING AND WEIGHING MECHANISM.
APPLICATION FILED JULY 31, 1920.

1,407,224.

Patented Feb. 21, 1922.

UNITED STATES PATENT OFFICE.

ALFRED S. SAMUELS, OF SAUGUS, MASSACHUSETTS.

HOLDING AND WEIGHING MECHANISM.

1,407,224.

Specification of Letters Patent. Patented Feb. 21, 1922.

Application filed July 31, 1920. Serial No. 400,392.

To all whom it may concern:

Be it known that I, ALFRED S. SAMUELS, a citizen of the United States, residing at Saugus, in the county of Essex and State 5 of Massachusetts, have invented certain new and useful Improvements in Holding and Weighing Mechanism, of which the following is a specification.

My invention relates to apparatus for 10 transferring materials of various kinds from one place to another, and particularly to apparatus of this class which comprises a suspended bucket, platform or other material-holding member that is moved back and forth between two places or locations at one of which said member is loaded and at the other unloaded.

An example of an apparatus of the class referred to is found in bucket cranes such 20 as are provided at wharves and on lighters and used to transfer coal and other materials from the hold of a barge or other boat to the wharf or a vessel. An apparatus of this kind comprises a bucket attached to 25 one end of a cable which extends upwardly from said bucket through a pulley block carried at the free end of a boom. The opposite end of the boom is movably mounted upon a suitable support so that said boom can 30 be swung laterally, and usually so that it can be swung up and down. Through well known mechanism the bucket cable is operated to raise and lower the bucket, the boom being shifted laterally on its support 35 to transfer the bucket to and fro. It has heretofore been customary to measure the material as it was shifted from one point to another, by counting the number of bucketsful transferred and multiplying the same 40 by the average weight of a single bucketful of material. This method of measuring, however, was inaccurate and therefore unsatisfactory and an object of my invention is to improve the construction of cranes of 45 this kind so that the actual weight of the material being handled thereby may be quickly and accurately ascertained.

To these ends my invention consists of an apparatus for transferring material from 50 one place to another including a bucket or other load holding member and characterized by the provision of means for weighing said load during transit.

Other features of my invention are here- 55 inafter pointed out.

In the accompanying drawings:

Figure 1 shows in side elevation and, in more or less diagrammatic fashion, a crane constructed in accordance with my invention.

Figure 2 is a front view of the upper end portion of the boom of the crane shown in Fig. 1.

Figure 3 is a plan view of the parts shown in Fig. 2.

Having reference to the drawings, 1 represents the boom of a crane pivotally mounted at 2 upon a support 3 which may be a car movable laterally upon rails or a lighter or the like (not shown). The boom 1 is 70 swung up and down, or adjusted, upon its pivot 2 as required by the usual mechanism including a cable 4. At its free end the boom 1 has a lever 6 pivotally mounted thereon at 5, one end of said lever being connected by a yoke 7 and link 8 with a pulley block 9. Through this block 9 extends a cable 10 to one end of which is attached a bucket 11 of ordinary construction. From bucket 11 the cable 10 extends upwardly 75 around the sheave 12 of block 9 and thence downwardly around a sheave 13 on support 3 to the usual windlass 14 also mounted upon said support. The opposite arm of lever 6 has connected to it one end of a wire cable 15 which extends downwardly from said lever around a sheave 16 mounted on support 3 to another lever 17 fulcrumed at 18 on said support, to which the other end of said cable is attached.

The lever 17 also has connected to it one end of a cable 19 which extends upwardly from said lever through a small pulley block 20 and thence downwardly to a piston 21 to which the opposite end is fastened. Piston 21 is arranged within a cylinder 22 fixed to support 3 and having its upper end connected by a pipe or conduit 23 with a reservoir 24 holding a supply of fluid under pressure such as compressed air or steam. By means 100 of a normally closed three-way valve, 25, communication between cylinder 22 and reservoir 24 is controlled. The block 20 is connected by a link 26 with a scale beam 27 fulcrumed at 28, said beam being made as 105 usual with graduations (not shown) and provided with adjustable weights 29, 291 and removable weights 30.

A stop 31 secured to boom 1 in position immediately below the arm of lever 6 to 110

which block 9 is connected normally supports said lever so that it carries bucket 11 and the weight of the load within the latter.

In operating the apparatus above described the bucket, after being loaded, is raised by means of cable 10 and windlass 14 and brought to rest at an elevated position. The operator then operates valve 25 to connect cylinder 22 with reservoir 24 which admits fluid under pressure into said cylinder above piston 21 and the latter is forced downwardly and acts through cable 19, lever 17, and cable 15 to swing lever 6 from the full line position to the dotted line position shown in Fig. 1, so that said lever is no longer supported by the stop 31 and consequently the bucket and its contents is then supported by one end of the pivoted lever 6, which is arranged at any ratio of leverage desired, and the weight is thus transmitted through cable 15, lever 17 and cable 19 to the lever 27. Levers 17 and 27 are arranged at any ratio of leverage desired and lever 27 is graduated as a scale beam in the usual manner. By adjustment of the weights while the parts are held in proper position the weight of the contents of bucket 11 is quickly ascertained. After thus weighing the contents of the bucket the operator reverses the position of valve 25 shutting off communication between cylinder 22 and reservoir 24 and connecting the upper end of the cylinder with the outside atmosphere through a port 32 provided in valve 25. The weight of the bucket 11 then acts to swing the lever 6 back into its full line position, where it is supported by the stop 31, the movement of the lever at this time acting through cable 15, lever 17 and cable 19 to return the piston 21 to the upper end of cylinder 22. The boom 1 is then moved as desired, the bucket dumped and then returned to the loading position. It may be desirable in practice to provide the pivots of levers 6 and 17 with ball bearings. As has been said, the leverage of levers 6 and 17 may be arranged as desired, so that the scale beam 27 will require relatively small weights to record and measure a heavy load in the bucket 11. The sliding weight 29 may obviously be adjusted to offset the weight of bucket and connections, while the net weight of the load may be recorded by sliding weight 291 or removable weights 30.

What I claim is:

1. An apparatus of the character described, comprising a load-holding member;

a boom; a pivoted lever at the free end of the boom; a scale beam; connections between opposite ends of the pivoted lever and the load-holding member and the scale beam respectively; a stop upon the boom limiting movement of the lever; means to separate the lever and the stop at will to cause the weight of the load to become effective upon the scale beam. 60 65

2. An apparatus of the character described, comprising a load holding member; a boom; a block; means through which said block is connected with said boom with provision for movement relatively thereto under the influence of the weight of said holder and its load; a stop for limiting movement of said block in one direction under the influence of the weight of said member and its load; a cable connected with said load holding member and extending through said block; a scale beam; and means connected with said beam and said connecting means for transferring the weight of the block and the parts carried thereby from said stop to 80 said scale beam. 70 75

3. In an apparatus of the character described, the combination of a transporting member that is movable laterally; a load holding member; means movably mounted on said transporting member for supporting said load holding member; a stop for limiting the movement of said supporting means relatively to said transporting member under the influence of the weight of said load holding member and its load; a scale beam; means connecting said scale beam with said supporting means, and means for adjusting said connecting means to cause the weight of said load holding member to operate said 90 95 beam. 85

4. An apparatus of the character described, comprising a boom; a pivoted lever mounted at the free end of the boom, a pulley-block sustained by one end of the pivoted lever; a load holding member sustained by a cable passing through the pulley-block; a stop upon the boom to support the pivoted lever; a connection from the other end of the pivoted lever to a scale beam; means to 100 105 raise the lever from the stop to cause the weight of the load to become effective upon the scale beam.

Signed at Boston, Massachusetts, this thirtieth day of July, 1920.

ALFRED S. SAMUELS.
